US00D998715S

(12) **United States Design Patent** (10) **Patent No.:** **US D998,715 S**
(45) **Date of Patent:** **** Sep. 12, 2023**

(54) **SCOOTER**

(71) Applicant: **Shenzhen Chitado Technology CO., LTD.**, Guangdong (CN)

(72) Inventors: **Fuqi Zhou**, Shenzhen (CN); **Huihai Zeng**, Shenzhen (CN); **Yang Zhang**, Shenzhen (CN); **Dianxuan Zhang**, Shenzhen (CN)

(73) Assignee: **Shenzhen Chitado Technology Co., Ltd.**

(**) Term: **15 Years**

(21) Appl. No.: **29/751,126**

(22) Filed: **Sep. 18, 2020**

(30) **Foreign Application Priority Data**

Sep. 10, 2020 (CN) 202030535553.3

(51) LOC (14) Cl. **12-11**

(52) U.S. Cl.

USPC **D21/423**

(58) **Field of Classification Search**

USPC D21/419, 421, 423, 760, 765, 771; D12/1, 8, 107, 110, 112-114
CPC . B62K 3/002; B62K 9/00; B62K 9/02; B62K 2202/00; B62K 13/00; B62K 11/00; B62K 11/02; B62K 11/06; B62K 11/10; B62K 15/00; B62K 17/00; B60Y 2200/126; H04W 4/40
